UNITED STATES PATENT OFFICE.

MANDEL BLOCK, OF CHICAGO, ILLINOIS.

THREAD-CUTTING DIE.

1,242,130.

Specification of Letters Patent. Patented Oct. 9, 1917.

Application filed November 22, 1916. Serial No. 132,762.

To all whom it may concern:

Be it known that I, MANDEL BLOCK, a citizen of the United States, residing at Chicago, in the county of Cook and State 5 of Illinois, have invented a certain new and useful Improvement in Thread-Cutting Dies, of which the following is a specification.

My invention relates to thread cutting dies such as are used by plumbers, steam fitters and others to cut threads upon pipes or rods. The object of the invention is to provide means for keeping the work clean during the process of cutting and to thereby 10 enable the die to produce a more perfect piece of work. I accomplish this briefly by furnishing the die with one or more brushes of proper type of a length preferably equal to the thickness of the die, said brush traveling in front of the chaser or cutting element and thereby keeping all of the threads and the surface of the work clean. The principle of the invention is illustrated in the accompanying drawings, in which Figure 1 15 is a face view of a die provided with my invention. Fig. 2 is a sectional view on line 2—2 of Fig. 1. Fig. 3 is a sectional view on the line 3—3 of Fig. 1. Fig. 4 is a perspective view of a die furnished with a 20 brush of somewhat modified construction.

Similar numerals refer to similar parts throughout the views.

The body of the die is of the ordinary type used in die stocks and it is furnished 25 with a plurality of chasers or thread cutting elements 2, of any suitable construction. Ordinarily the chasers will extend from one face of the die body to the other but the cutting threads will not extend quite the 30 entire length of the chaser, for reasons understood by those familiar with this art.

In the form shown in Figs. 1, 2 and 3 35 the brushes consist of wire bristles 3, extending from a base 4, the base being so rabbeted into the inside of the die body position that when the die is taking a cut the brush will be in advance of the chaser. The 40 number of brushes may be varied, Fig. 1 showing a die with four chasers and two 45 brushes and Fig. 4 showing one with four 50 brushes.

chasers and four brushes. By preference the brushes extend from one face of the die body to the other, as best shown in Figs. 2 and 3.

The form shown in Fig. 4 is similar to 55 the one shown in the other figures, except that the brushes are of hog bristles or other suitable non-metallic but fibrous material. In this case, as before, the bristles 5 are mounted upon bases 6 rabbeted into the inside of the die. In the form illustrated in Fig. 4 the bristles do not extend in a continuous row in which the bristles touch each other but they do extend over a considerable part of the thickness of the die and when 60 spread, as they will be when in action, the acting portions of the bristles come fairly closely together, at least for that portion of the work where the cut is actually being taken.

In operation the die is started upon the work, as suggested in Fig. 2, and is then rotated by a hand stock or otherwise. The brushes traveling in front of the chasers will continually brush the chips or cuttings 75 from the surface of the work and thereby enable the chasers to take a clean and perfect cut. It will be understood by those familiar with thread cutting that it is the custom to pour oil or thick soapy water 80 upon the surface of the work during the cutting operation to facilitate the cutting process. This oil or other lubricant, while it assists in the cutting operation, tends to make the chips stick to the work and these 85 frequently get between the chaser and the work and cause the production of imperfect threads. These chips are, of course, being formed at all points where the chasers are cutting into the work, but with this device 90 the brushes cover all, or a large part of the surface of the work which is actually being cut and thereby keeps the surface clean and smooth. The brushes in the preferred design are arranged practically radially, with 95 the result that as they are resilient they operate to flick the cuttings forcibly from the surface of the work. My device, therefore, is very effective in its action and produces a clean perfect cut, with no addi- 100

tional labor on the part of the operator and little additional cost to the manufacturer of the die.

I claim:

- 5 A thread cutting die having a solid body with a central opening and chasers fastened therein and extending radially inward, and a brush fastened to the body approximately

midway between two chasers, the axial length of the brush being approximately as great as the axial length of the chaser, the brushes having resilient bristles for contacting and sweeping the surface of the work.

In witness whereof, I have hereunto subscribed my name.

MANDEL BLOCK.
